UNITED STATES PATENT OFFICE.

WILLIAM J. ELDER AND CHARLES N. MOREHOUSE, OF OSWEGO, NEW YORK, ASSIGNEES
TO THE DIAMOND MATCH COMPANY, OF CHICAGO, ILLINOIS, A CORPORATION OF
ILLINOIS.

APPARATUS FOR APPLYING ADHESIVE TO WRAPPING-PAPER.

1,399,051.

Specification of Letters Patent.

Patented Dec. 6, 1921.

Application filed April 2, 1920. Serial No. 370,630.

To all whom it may concern:

Be it known that we, WILLIAM J. ELDER and CHARLES N. MOREHOUSE, both citizens of the United States, and residents of the 5 city of Oswego, in the county of Oswego and State of New York, have invented certain new and useful Improvements in Apparatus for Applying Adhesive to Wrapping-Paper, of which the following is a specifica-
10 tion.

The object of this invention is to provide mechanism of simple and efficient construction and operation for facilitating the economical application of paste, or other 15 suitable adhesive substance, to wrapping paper as a step in the operation of packaging boxes of matches and the like.

The invention, generally stated, consists in the provision of a unitary bodily reciprocable paste receptacle having a plurality of discharge openings so constructed and arranged that a wrapper sheet can be readily positioned in such relation to the openings that paste can be economically deposited 25 thereby at predetermined spots on the sheet, such spots being so located that the adhesive substance thereon when the articles are wrapped unites the contiguous folds or layers of the wrapper upon the top and ends 30 of the package.

The invention also comprises a paste receptacle having a guide device constructed and arranged to facilitate and insure the accurate positioning of the boxes on the 35 wrapper.

The invention also comprises novel features of construction and combinations of parts which will be hereinafter described and claimed.

40 In the drawings—

Figure 1 is a perspective view of a wrapper pasting apparatus embodying a simple form of our invention, showing a pile of wrapper sheets positioned beneath the paste receptacle.

Fig. 2 is an end elevation of the apparatus.

Fig. 3 is a perspective view of one corner of the bottom plate, as inverted, and the adjacent portion of the paste receptacle, showing one of the discharge openings of the plate and also the depending portion of a side wall of the receptacle.

Fig. 4 is a horizontal section of the apparatus, on the line 4—4 of Fig. 2, showing a group of boxes positioned on the wrapper 55 sheets.

Fig. 5 is a longitudinal vertical section of the apparatus, on the line 5—5 of Fig. 2.

Referring to the drawings, 5 designates a table having thereon suitably-disposed 60 guides, such as the adjustable angle-pieces 6, adapted, in the present form of our invention, to determine the position on the table of a pile of wrapper sheets, as 7, to which, successively, paste or other adhesive 65 substance is properly applied. Obviously the sheets may be fed or delivered successively to and positioned on the table, either manually or mechanically.

A vertically-movable paste containing and 70 feeding receptacle of novel construction is mounted to overhang the sheet or sheets on the table. This receptacle, in its preferred form, comprises a capacious chamber 8 opening into three depending feed chambers, one 75 (9) of which is at the rear and the others (10) project forwardly at the respective sides of the structure. The walls 11 of the structure are shaped to provide funnel or hopper-like feed chambers, the lower ends of 80 which bound and communicate with suitably-located discharge openings 12, 12' in a horizontal bottom plate upon which the structure is bodily supported. This plate comprises a main portion 13 having the opening 85 12 with which the rear chamber 9 communicates, and two forward end extensions 14 having the openings 12' with which the respective side chambers 10 communicate.

The discharge openings are formed and 90 arranged to overlie the wrapper sheet at or near its rear and side edges respectively, and hence when the bottom plate, with the receptacle, is lowered upon the sheet the impact causes a small quantity of the paste contents 95 of the receptacle to flow through the discharge openings to and upon the proximate parts of the sheet.

The outer walls of the respective feed chambers preferably depend slightly below 100 the bottom plate, as indicated at 15, so as to bear upon the sheet when the receptacle is in down position, and thus maintain the discharge openings slightly above the surface

of the paper to permit the free discharge of the paste from the chambers.

We preferably provide each of the feed chambers with an adjustable gate valve

5 which depends into the respective discharge openings. In the present instance each valve comprises a plate 16, the upper end of which is provided with a curved lip 17 adapted to be hung on the top of the adjacent outer wall of the structure, which wall is provided with a set-screw 18 that extends through a suitably-disposed leaf spring 19 on the exterior of the wall and bears against the movable plate in such a manner that the 10 plate can be nicely adjusted to vary the width of the discharge opening, as occasion may require.

As a simple and efficient means to facilitate and insure the positioning of a group 20 of boxes in proper relation to the pasted portions of the wrapper, we provide, in the space between the depending side chambers of the paste receptacle, a guide device comprising, preferably, two spaced-apart end 25 walls 20 and a rear connecting wall 21 therefor; which walls are conveniently supported on the bottom plate for the receptacle as shown. When the receptacle is in its normal or down position this guide device lies 30 in close relation to the positioned wrapper and thus serves as an efficient stop and positioning means for a group of boxes (B) manually imposed on the wrapper and slid between the side chambers. (See Fig. 4.)

35 Any suitable means for bodily raising the paste-receptacle may be employed. In the present instance, the bottom plate is provided at its respective ends, adjacent the rear, with up-standing lugs 22 which are pivotally connected to a pair of rearwardly-extending arms 23 fast on the respective ends of the rock-frame 24 pivoted to up-standing lugs 25 secured to the table. By this construction the receptacle, together 40 with the bottom plate, is flexibly supported and thus permitted normally to rest by gravity in horizontal position upon the underlying wrapper or wrappers. A simple mode of operating the receptacle consists 45 in connecting the rear projecting end of one of the arms 23, by means of a link 26, with a suitably-disposed foot treadle lever 27, by the operation of which the rock-frame and its arms 23 can be actuated to raise the receptacle bodily above the wrapper in order 50 to permit the removal and manipulation of the pasted sheet and the imposed group of boxes thereon. This done the receptacle is permitted to drop and thus apply paste to

55 a succeeding wrapper and also permit the accurate positioning of another group of boxes on the wrapper, and so on.

It is to be understood that we do not limit our invention to the details of construction

herein shown and described, as the same 65 may be modified within the principle of our invention and the scope of the appended claims.

We claim—

1. In an apparatus for applying adhesive 70 to wrappers, a wrapper support, a unitary paste receptacle comprising a main upper chamber and a series of depending feed chambers integral with and supplied from said upper chamber, said feed chambers terminating at their lower ends in contracted discharge openings which overhang the adjacent rear and side edges of the wrapper and afford a space to receive the packages to be wrapped, and connections permitting 75 bodily vertical reciprocation of said receptacle above the wrapper support.

2. In an apparatus for applying adhesive to wrappers, a wrapper support, a unitary paste receptacle comprising a main upper 80 chamber and a series of depending feed chambers integral with and supplied from said upper chamber, said feed chambers terminating at their lower ends in contracted discharge openings which overhang the adjacent rear and side edges of the wrapper and afford a space to receive the packages to be wrapped, means for regulating the size 85 of the said openings, and connections permitting bodily vertical reciprocation of said receptacle above the wrapper support.

3. In an apparatus for applying adhesive to wrappers, a wrapper support, a unitary paste receptacle comprising a main upper chamber and a series of depending feed 90 chambers integral with and supplied from said upper chamber, said feed chamber terminating at their lower ends in contracted discharge openings which overhang the adjacent rear and side edges of the wrapper and afford a space to receive the packages to be wrapped, means positioned to rest 95 upon the wrapper and maintain said openings slightly above the surface of the wrapper, and connections permitting bodily vertical reciprocation of said receptacle above the wrapper support.

4. In an apparatus for applying adhesive to wrappers, a wrapper support, a unitary paste receptacle including two spaced-apart 100 depending feed chambers having contracted discharge openings at their lower ends, a package guide supported between said chambers, and connections permitting bodily reciprocation of said receptacle above the 105 wrapper support.

5. In an apparatus for applying adhesive to wrappers, a wrapper support, a unitary paste receptacle comprising a main upper chamber, a depending rear feed chamber 110 and two spaced-apart depending side feed chambers, each of said feed chambers having a contracted lower discharge portion,

a supporting bottom plate having openings therein in communication with said discharge portion, a package guide supported on said receptacle in the space between the 5 side feed chambers, means for flexibly supporting said receptacle to permit it normally to drop by gravity on an underlying

wrapper, and means for temporarily raising said receptacle.

Signed at Oswego, in the county of Oswego and State of New York this 30 day of March, A. D. 1920.

WILLIAM J. ELDER.

CHARLES N. MOREHOUSE.
